UNITED STATES PATENT OFFICE.

HENRY J. ELLERS, OF ROTTERDAM JUNCTION, NEW YORK.

CHECKREIN-FASTENER.

SPECIFICATION forming part of Letters Patent No. 591,462, dated October 12, 1897.

Application filed December 30, 1896. Serial No. 617,442. (No model.)

To all whom it may concern.

Be it known that I, HENRY J. ELLERS, a citizen of the United States, residing at Rotterdam Junction, county of Schenectady, and 5 State of New York, have invented certain new and useful Improvements in Checkrein-Snaps, of which the following is a specification.

The invention relates to such improvements; and it consists of the novel construction and combination of parts hereinafter described and subsequently claimed.

Reference may be had to the accompanying drawings, and the letters of reference marked 15 thereon, which form a part of this specification.

Similar letters refer to similar parts in the several figures therein.

Figure 1 of the drawings is a top plan view 20 of my improved snap. Fig. 2 is a side view of the same in engagement with a check-hook. Fig. 3 is a cross-section taken at the broken line 3 3 in Fig. 1. Fig. 4 is a plan view of a portion of the casting before the rubber and 25 clip-plate are inserted. Fig. 5 is an end view of the same after the plates are inserted and before the arms are swaged down onto the plate.

The object of my invention is to provide a 30 checkrein-snap that can be easily and quickly secured detachably to the check-hook of a harness and that cannot be accidentally detached and that will not injure the hook.

My invention consists of a clip or eye 35 secured to the checkrein and adapted to receive the check-hook and provided with a yielding plunger which grips the hook, also of cushions on the plunger and clip to engage the hook, as hereinafter more fully set forth and 40 claimed.

The body part of the snap comprises in an 45 integral malleable casting a cylindrical barrel A, having at one end an attaching-eye A', adapted to receive the checkrein, and at the other end the arms A², adapted to support a bridge-plate or eye-clip B and form therewith an eye adapted to receive the check-hook H. (Shown in part in Fig. 2.) The barrel-chamber (indicated by the dotted lines A³ in Fig. 50 1) contains in its closed end a coil-spring S and the shank or spindle of plunger P. The eye-clip plate B is inserted between the arms A², as shown in Fig. 5, and secured therein by swaging the ends of the arms down upon

the plate to the position shown in Fig. 1, the 55 ends of the plate resting upon the ledges A⁴. The ends of the plate are concaved or cut in to fit the beveled or wedge-shaped arms, as seen in Fig. 5, so that the plate cannot be accidentally displaced while in use. When desired, a cushion-plate B', of rubber or other soft material, similar in form to the eye-clip plate, may be interposed between the latter plate and the ledges on the arms to engage the hook H when the hook is inserted in the 60 eyes, as seen in Fig. 2. The plunger P projects from the barrel-chamber and is forced by the spring out toward or against the clip-plate or the intervening cushion-plate. The head of the plunger is also provided with a 70 cushion P', which may be of the same material as the cushion-plate. The end of the plunger is split to receive the cushion-tongue P² and the split partially closed to pinch the tongue. The cushion-plate and the cushion 75 plunger-head are adapted to engage the eye-inserted hook on its opposite sides and prevent the snap from being accidentally detached from the hook. The plunger-actuating spring causes the hook to be firmly gripped 80 between the two cushions. The cushions also serve to prevent the hook from being marred or perceptibly worn by the movements of the snap while in use.

What I claim as new, and desire to secure 85 by Letters Patent, is—

In a checkrein-snap, the combination with a malleable casting comprising a slideway-barrel, provided at one end with means for securing a checkrein thereto, and at the other 90 end with a pair of arms severally provided at the outer end with a shoulder, of a cushion and cushion-supporting plate inserted between said arms and secured in engagement with the shoulders thereon by overlapping 95 lugs formed by upsetting portions of the arms upon the outer side of said plate, a spring-actuated plunger inserted in the barrel-slideway, and a head on said plunger movable between said arms toward and from said cushion, substantially as described.

In testimony whereof I have hereunto set my hand this 14th day of November, 1896.

HENRY J. ELLERS.
